ALMON B. GLOVER, OF BIRMINGHAM, CONNECTICUT.

Letters Patent No. 75,675, dated March 17, 1868.

IMPROVEMENT IN MACHINE FOR HEADING BOLTS.

The Schedule referred to in these Letters Patent and making part of the same.

TO ALL WHOM IT MAY CONCERN:

Be it known that I, A. B. GLOVER, of Birmingham, in the county of New Haven, and State of Connecticut, have invented a new Improvement in Machines for Heading Bolts; and I do hereby declare the following, when taken in connection with the accompanying drawings and the letters of reference marked thereon, to be a full, clear, and exact description of the same, and which said drawings constitute part of this specification, and represent, in—

Figure 1, a top view.

Figure 2, a side view.

Figure 3, a section on line $z z$, looking toward the blank-holder; and in

Figure 4, a longitudinal central section.

This invention relates to an improvement in that class of machines used for the manufacture of bolts, such as have formed upon one end a small square head, and directly thereunder a round collar, and which are known to the trade by the title of "bed-screws;" and

The invention consists, first, in the arrangement and operation of the follower, so that, after the heading-die has closed upon the head of the bolt, the follower will advance, perfectly fill, and complete the head; and combining therewith an automatic finger, which at the proper time presents itself to the holding-die for the purpose of supporting the blank.

To enable others to construct and use my improvement, I will proceed to describe the same, as illustrated in the accompanying drawings.

A is the bed-plate or frame for supporting the operative mechanism of the machine; B, the driving-shaft, resting and so as to revolve in bearings, C, and driven by the application of power thereto through the pulley D. E is the fixed holding-die, and F a corresponding movable die, the face of each being formed to receive one-half the blank to be headed, and the movable die is closed against the fixed die, as denoted in red, fig. 1, by means of the cam G, acting through the toggle-joint H, which said movement draws the die F from or forces it to the fixed die E, so that when the blank is laid between the dies F and E, and the dies closed, the blank is securely held. Between the two dies, and near their rear end, a supporting-pin, α , is fixed in one die, and an opening formed in the other die to receive the said pin, and the said pin placed so as to be in the proper position to support the blank when laid between the dies. The other end of the blank is supported by a finger, b, pivoted to the frame, and so that when raised, as denoted in figs. 1 and 3, the blank will rest on the pin α and finger b; and, when the dies are closed, then an arm, c, operated by the cam I, is thrown back, as denoted in red, fig. 3, and causes the finger b to drop out of the way, as denoted in red, fig. 3, and when again the finger is wanted, at the proper time the arm c is moved forward to raise the finger to the first position, as described. Thus the blank is supported until grasped and headed by the dies F and E.

In the rear of and entering the dies F and E, is arranged an adjustable spindle, L, entering the said dies, so that the end of the blank resting against the said spindle, governs the length of the bolt below the head, and is adjusted to different lengths by nuts, d and e, and the said spindle is moved to throw the bolt from the dies after the head is formed, by means of a cam, K, through the lever M.

The heading-die f is fixed in a die-holder, N, as seen in fig. 4, and the said die-holder attached to a slide, O, and moved to and from the holding-dies in proper guides, P, by the action of a cam, R, upon the slide, to throw the die forward upon a lever, S, to return the slide, as seen in fig. 4. Through the said slide, and entering the heading-die f, is a follower, h; or, if deemed necessary, (as, I think, it is at least expedient,) I place a hardened block, i, into the die before the follower. The said follower extends back through the slide at the rear, and so that the same cam R will operate therein. The distance which the follower extends through the slide is adjusted by nuts, n.

When the cam R revolves, as denoted in fig. 4, it first forces the slide, with the heading-die, forward; then, passing on the said cam, strikes the end of the follower h, and forces that forward to the extent of its projection through the slide.

By this operation, in the first movement, the blank enters the heading-die, and upsets the end of the blank to form the neck and square head. The last short movement of the follower adds an extra pressure after the

movement of the heading-die has ceased, and forces the metal to completely and perfectly fill the die. After the head has been thus formed, the slide returns, and as it returns another cam, T, strikes the slide U, which is attached to the follower h, as seen in fig. 1, and forces the follower still further forward to drive the head of the bolt from the heading-die. Thus the bolt is inserted into the machine, and headed completely in the most perfect manner.

Having thus fully described my invention, what I claim as new and useful, and desire to secure by Letters Patent, is—

1. The combination of the cam R, slide O, and die f, with the cam T, auxiliary slide U, screw-threaded follower h, and nuts n n, all constructed and arranged as described.

2. The supporting-finger b, in combination with the holding-dies F and E, when constructed and arranged so as to be presented and retire at the proper time, as and for the purpose set forth.

ALMON B. GLOVER.
